US0D1092451S

(12) **United States Design Patent** (10) **Patent No.:** **US D1,092,451 S**
(45) **Date of Patent:** **** Sep. 9, 2025**

(54) **MICROPHONE**

(71) Applicant: **Harman International Industries, Incorporated**, Northridge, CA (US)

(72) Inventor: **Jonas Ceppa**, Shenzhen (CN)

(73) Assignee: **Harman International Industries, Incorporated**, Northridge, CA (US)

(**) Term: **15 Years**

(21) Appl. No.: **29/910,149**

(22) Filed: **Aug. 16, 2023**

(51) LOC (15) Cl. **14-01**

(52) U.S. Cl.

USPC **D14/225; D14/228**

(58) **Field of Classification Search**

USPC **D14/228, 225, 240; 381/380-381, 92,**

381/363, 111

CPC **H04R 25/00; H04R 1/08; H04R 1/04; H04R**

19/04; H04R 1/1083

(57) **CLAIM**

The ornamental design for a microphone, as shown and described.

DESCRIPTION

FIG. 1 is a top, front perspective view of a microphone showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines immediately adjacent the shaded areas represent the bounds of the claimed design while all other broken lines are directed to environment in which the design resides; the broken lines form no part of the claimed design.

1 Claim, 7 Drawing Sheets
